CAR COUPLER

Arthur J. Bazeley, Cleveland, Ohio, assignor to
 National Malleable and Steel Castings Company, Cleveland, Ohio, a corporation of Ohio

Application September 9, 1929, Serial No. 391,129

12 Claims. (Cl. 213—100)

This invention relates to car couplers of the vertical plane type, such as are shown in the Letters Patent of John Willison, No. 1,201,665, dated October 17, 1916 and No. 1,614,517, dated January 18, 1927 and in the Letters Patent of William Blackmore et al., No. 1,647,497, dated November 1, 1927, in which the coupler comprises a coupler head, a lock and a suitable mechanism for actuating the lock. The invention particularly comprises the provision of means for effectively preventing the lock from creeping out of locking position when the couplers are under draft, and at the same time permitting ready retraction of the lock to unlocking position, even though the couplers be tightly interengaged, when it is desired to effect uncoupling. In the patent to Blackmore, No. 1,647,497, November 1, 1927, there is shown a construction effective in preventing creeping of the lock, such construction consisting of a locking face non-parallel with respect to that surface of the lock which rests against the inner surface of the coupler lug 3, whereby the forwardmost edge of the lock is thicker than the rear part of the locking face and a wedging action between said face and that of the opposing lock is obtained, preventing either of said locks from working rearwardly. Such an anti-creep arrangement however, is undesirable for couplers on cars provided with pneumatic buffers the faces of which are located ahead of the coupling line, which buffers must be compressed in order that coupling may be effected. With such pneumatic buffers the couplers are maintained tightly engaged with each other so that when tapered locks such as shown in the aforesaid patent to Blackmore et al., are employed it is usually impossible to retract the said locks for uncoupling except by first blocking one of the cars and pushing the other against it with considerable pressure. This has led to the employment, in couplers for use with said pneumatic buffer arrangements, of a lock having its locking face parallel to its opposite face, but with such construction there is no provision for prevention of creeping of the lock. Through my invention an effective anti-creep means is provided, which means at the same time permits the lock to be readily withdrawn when it is desired to effect uncoupling even though the couplers be tightly engaged under the influence of the pneumatic buffers. The lock is also permitted to move rearwardly during the operation of coupling with an opposing coupler. The invention also comprises various features which will be hereinafter described and claimed.

55 In the accompanying drawings;

Fig. 1 is a side elevation of a coupler embodying my invention, the parts being shown in locked position.

Fig. 2 is a view partly in plan and partly in section on line II—II of Fig. 1, a portion of an opposing coupler being shown in dot-dash lines in engagement with the previously mentioned coupler.

Fig. 3 is a side elevation similar to Fig. 1 but showing the lock moved partly to the rear as in the act of coupling with an opposing coupler.

Fig. 4 is an end elevation corresponding to Fig. 3.

Fig. 5 is a partial sectional view taken on line V—V of Fig. 3.

Fig. 6 is a side elevation showing the lock being retracted by the lock lift lever as in uncoupling.

Figs. 7, 8, 9, and 10 are views showing the lock in top plan, side elevation, bottom plan, and front elevation, respectively.

Figs. 11 and 12 are views showing the lock operating lever in plan and side elevation respectively.

Fig. 13 is a detail view in rear elevation showing a portion of the lock operating lever, and

Fig. 14 is a view partly in vertical section and partly in side elevation, on a reduced scale, showing a car equipped with pneumatic buffer means, with which arrangement my invention is especially advantageous.

Fig. 15 is a vertical sectional detail view illustrating a modified feature of the invention.

Referring to the drawings the coupler comprises a head 2 having a buffering jaw 3 and a pulling jaw 4. Said head also comprises a buffering face 5 arranged on an axis inclined laterally to the line of draft. The pulling jaw 4 has a laterally extending recess 4a to receive the complementary jaw 3 of the opposing coupler head, and its pulling face 7 engages a complementary face 8 of the buffering jaw on the opposing coupler head.

The lock 9 of the coupler operates in a pocket or cavity 10 in the coupler head. Journaled on a bolt 11 which passes through said head is a lock operating lever 12. The latter consists of two arms 13 and 14 joined at their rear ends by a web 15, said arms being apertured for the passage of the bolt 11. An extension 13' of the arm 13 is adapted to have connected thereto a chain or other suitable element for actuating the lever 12 as will be readily apparent. The arm 13 lies outside the coupler head while arm 14 projects inside the cavity 10. The arm 14 is provided with a cam surface 16, which when the lever is rotated counter-clockwise from its Fig. 1 position, comes

110

into contact with a surface 17 on the lock and retracts the latter. The forward end 18 of arm 14 lies in the path of a stop portion 19 of the lock 9 when the lever 12 is in its normal locking position, to limit the rearward movement of the lock when the latter is driven rearwardly by a coupling impact and to prevent the lock from moving so far back into the coupler as to preclude coupling up under rapid impact conditions. It 10 will be noted that the locking face 9' of the lock is shown parallel to its opposite face 9''.

For preventing creeping of the lock from locked position when engaged with an opposing lock and at the same time permitting the lock to be 15 freely retracted for unlocking even though the couplers be tightly engaged with each other, I have provided the following means.

On the rear face of the stop portion 18 of lever arm 14 I provide a beveled surface 20; while the 20 lock 9, just to the rear of the stop surface 19, is provided with a beveled shoulder 21. The tendency of the locks to creep out of locking position occurs when the couplers are under draft (as indicated in Fig. 2) and when there is vertical sliding 25 between said couplers due to uneven track. When the couplers are under draft or a pulling strain the opposing locks 9 of said couplers press each other tightly against the surface 22 of the lug 3 of the corresponding coupler. Now if either 30 lock starts to creep rearwardly, its surface 21 engages the corresponding surface 20 of the adjacent lock lever 12, with the result that the rear part 9'' of the lock is crowded against the lock guiding wall 23 of the coupler. It will be apparent 35 that the lock is now effectively pinched against rearward creeping; the rear part of the lock being in contact with wall 23, the lock surface 21 engaged with lock lever surface 20, and the forward locking face 9' of said lock being 40 in engagement with the face of the opposing lock.

To enable the lock to move rearwardly freely during coupling operations I have shown said lock narrowed down at 24, to the rear of its locking face. With this construction, when the lock 45 is pushed rearwardly by an opposing coupler during a coupling operation the forward portion of the lock can move away from the surface 22 of coupler lug 3 so that the lock can ride up over the beveled anti-creep surface 20. During a 50 coupling operation there is no pressure against the locking face 9' and thus said lateral movement may readily take place. In Fig. 5 the lock is shown in the act of moving rearwardly during coupling, a small clearance or gap being shown 55 at 25 between face 9'' of the lock and surface 22. Since the anti-creep surfaces are nearer the lower end of the lock it is necessary only that the lower end of the lock move laterally, the top end of the lock sliding back and forth in the usual 60 way. Fig. 4, it will be noted, shows the gap 25 at the bottom end and not at the top of the lock. Instead of providing a narrow portion of the lock, the lock guide wall 23 may be cut away as shown at 23' in Fig. 15 to permit lateral movement of 65 the forward part of the lock during a coupling operation.

When it is desired to uncouple opposing couplers the lock lever 12 is turned counter-clockwise from its Fig. 1 position. This rotation of 70 said lever first raises the stop 18 and anti-creep surface 20 out of the path of stop surface 19 and anti-creep surface 21, respectively, of the lock 9. Upon continued rotation of said lever 12 the lock is drawn rearwardly, through the engagement of lug 16 with surface 17, without any 75

necessity for lateral movement of the lock. It will thus be evident that the couplers can be uncoupled, even when under draft, without any hindrance from the anti-creep means.

It will be seen that my invention is especially 80 advantageous in connection with couplers on cars equipped with pneumatic buffers the faces of which extend beyond the coupling line. Fig. 14 shows a portion of one of such cars partly in vertical section and partly in side elevation. The coupler, which is designated generally as 27, is positioned between pneumatic buffers 28 (only one of which is shown); the face of each buffer extending beyond the coupler. As has been 85 previously pointed out when such cars are coupled together the buffers are compressed and the couplers are constantly under the influence of draft stress resulting from the buffer compression. It will be apparent that my invention provides an 90 effective means for preventing creeping of the coupler locks out of locking position and at the same time for enabling the ready unlocking of the couplers even though the latter are held tightly engaged by the compressed buffers.

The terms and expressions which I have employed are used as terms of description and not of limitation, and I have no intention, in the use of such terms and expressions, of excluding any 95 mechanical equivalents of the features shown and described or portions thereof, but recognize that various structural modifications are possible within the scope of the invention claimed.

What I claim is:

1. In a car coupler, a head, a lock mounted in 110 said head and movable to a position for overlapping the lock of an opposing coupler, means for preventing creeping of the lock out of locking position and means operable to first throw said preventing means out of action and to thereafter shift the lock to coupler unlocking position.

2. In a car coupler, a head, a lock mounted in 115 said head and movable to a position for overlapping the lock of an opposing coupler, means for operating said lock, and means on said operating means cooperating with said lock for preventing creeping of the lock out of locking position.

3. In a car coupler, a head, a lock mounted in 120 said head and movable to a position for overlapping the lock of an opposing coupler, an arm for operating said lock, and means comprising co-operating surfaces on said arm and said lock for preventing creeping of the lock out of locking position.

4. In a car coupler, a head, a lock movably mounted in a cavity in said head to assume a projected locking position and a retracted unlocking position, said lock when in locking position being adapted to overlap the lock of an opposing coupler, means for preventing creeping of the lock out of locking position, and means operable to throw said preventing means out of action and subsequently to shift the lock to coupler unlocking position.

5. In a car coupler, a head, a lock movably mounted in a cavity in said head to assume a projected locking position and a retracted unlocking position, said lock when in locking position being adapted to overlap the lock of an opposing coupler, an arm for operating said lock, and an inclined surface on said arm cooperating with said lock for preventing creeping of the lock out of locking position.

6. In a car coupler, a head, a lock movably mounted in a cavity in said head to assume a 145

- projected locking position and a retracted unlocking position, said lock when in locking position being adapted to overlap the lock of an opposing coupler, an arm for operating said lock, and means comprising inclined surfaces on said arm and said lock, respectively, for preventing creeping of said lock out of locking position. 80
7. In a car coupler, a head, a lock movably mounted in a cavity in said head to assume a projected locking position and a retracted unlocking position, said lock when in locking position being adapted to overlap the lock of an opposing coupler, an arm for operating said lock, inclined surfaces on said arm and said lock, respectively, for preventing rearward creeping of the lock out of locking position, a clearance being provided between said lock and a wall of said cavity for permitting limited lateral movement of the lock to clear the inclined surface on said arm so that said lock may move rearwardly under the impact of an opposing coupler during a coupling operation. 85
8. In a car coupler, a head, a lock mounted in said head and movable to a position for overlapping the lock of an opposing coupler, means for operating said lock, and means movable with said operating means and cooperating with said lock for preventing creeping of the lock out of locking position. 90
9. In a car coupler, a head, a lock mounted in said head and movable to a position for overlapping the lock of an opposing coupler, means for preventing creeping of the lock out of locking position, and means for throwing the first mentioned means out of action independently of movement of the lock. 95
10. In a car coupler, a head, a lock mounted in said head and movable to a position for overlapping the lock of an opposing coupler, means for operating said lock, and means controlled by said operating means and cooperating with a portion of said lock for positively preventing creeping of the lock out of locking position. 100
11. In a car coupler, a head, a lock movably mounted in a cavity in said head to assume a projected locking position and a retracted unlocking position, said lock when in locking position being adapted to overlap the lock of an opposing coupler, means for preventing creeping of the lock out of locking position, said lock being adapted to non-wedging engagement with the lock of an opposing counterpart coupler, whereby said lock may be withdrawn to unlocking position even though the opposed couplers are under draft, the parts being so constructed and arranged as to require throwing of the preventing means out of action before the lock can be disengaged from the lock of an opposing coupler, and means for throwing said preventing means out of action as a prerequisite to movement of the lock to a position out of engagement with the lock of an opposing coupler. 105
12. In a car coupler, a head, a lock movably mounted in said head to assume a projected locking position and a retracted unlocking position, said lock when in locking position being adapted to overlap the lock of an opposing coupler, means for preventing rearward creeping of the lock out of locking position, means providing for free rearward movement of the lock under the impact of an opposing coupler during a coupling operation, the locking face of said lock being parallel to its opposite face whereby said lock may be withdrawn to unlocking position even though the opposing couplers are under draft. 110
